CLAIM

The ornamental design for a docking bottle, as shown and described.

DESCRIPTION

FIG. 1 is a perspective view of a docking bottle showing the new design;

FIG. 2 is a top view of the docking bottle;

FIG. 3 is a bottom view of the docking bottle;

FIG. 4 is a front view of the docking bottle;

FIG. 5 is a back view of the docking bottle;

FIG. 6 is a left side view of the docking bottle; and,

FIG. 7 is a right side view of the docking bottle.

The broken lines in the drawings depict portions of the docking bottle that form no part of the claimed design.
